(57) **CLAIM**

The ornamental design for a saw blade, as shown and described.

DESCRIPTION

Cross reference is made to copending U.S. design patent application Ser. No. 29/614,815 entitled "Saw Blade" by Grolimund et al., filed on even date herewith.

FIG. 1 is a perspective view of a saw blade showing our new design;

FIG. 2 is a left side elevational view of the saw blade of FIG. 1;

FIG. 3 is an enlarged detail view of a portion of the saw blade in the identified area of FIG. 2;

FIG. 4 is a right side elevational view of the saw blade of FIG. 1;

FIG. 5 is an enlarged detail view of a portion of the saw blade in the identified area of FIG. 4;

FIG. 6 is a top plan view of the saw blade of FIG. 1;

FIG. 7 is a bottom plan view of the saw blade of FIG. 1;

FIG. 8 is a front elevational view of the saw blade of FIG. 1; and,

FIG. 9 is a rear elevational view of the saw blade of FIG. 1. The dashed broken lines shown in the drawings illustrate portions of the saw blade that form no part of the claimed design. The dot-dash broken lines shown in the drawings illustrate a boundary line and form no part of the claimed design. The dot-dot-dash broken lines shown in the drawings identify the enlarged detail views of FIGS. 3 and 5 and form no part of the claimed design.
